UNITED STATES PATENT OFFICE

JAMES BRADLEY, OF PHILADELPHIA, PENNSYLVANIA

DESIGN FOR A COMBINED AUTOMOBILE HOOD AND RADIATOR

Application filed December 27, 1929. Serial No. 33,955. Term of patent 7 years.

To all whom it may concern:

Be it known that I, JAMES BRADLEY, a citizen of Ireland, residing at Philadelphia, in the county of Philadelphia and State of Pennsylvania, have invented a new, original, and ornamental Design for a Combined Automobile Hood and Radiator, of which the following is a specification, reference being had to the accompanying drawings, forming a part thereof.

The figure is a perspective view of a combined automobile hood and radiator showing

my new design. The series of short ridges or corrugations formed on the front of the hood adjacent the radiator shell extend from the bottom edge of said hood at one side all the way along the front edge to the bottom edge of the other side of said hood.

I claim:

The ornamental design for a combined automobile hood and radiator, as shown and described.

JAMES BRADLEY.
